UNITED STATES PATENT OFFICE.

FREDERICK W. KRECH, OF CHICAGO, ILLINOIS, ASSIGNOR OF ONE-HALF TO M. FRED DATTELZWEIG, OF CHICAGO, ILLINOIS.

HAT-FASTENING DEVICE.

1,070,704.

Specification of Letters Patent. Patented Aug. 19, 1913.

Application filed September 6, 1912. Serial No. 718,860.

To all whom it may concern:

Be it known that I, FREDERICK W. KRECH, a resident of Chicago, in the county of Cook and State of Illinois, have invented certain 5 new and useful Improvements in Hat-Fastening Devices, of which the following is a specification.

My invention relates to an improved hat fastening device and may be considered as 10 an improvement over the device shown in my co-pending application Serial No. 706,962, filed July 1, 1912. In the arrangement of this copending application a spring is connected between the point of the pin and 15 the pin supporting structure. This spring is apt to interfere with the proper insertion of the pin in the hair and the object of my present invention is therefore to eliminate the spring from the end of the pin and to 20 place it where it will not interfere with proper engagement of the pin with the hair.

Another object is to provide a more improved mechanism for detachably connecting the pin supporting structure to the hat 25 and to adapt such supporting structure to receive and entirely inclose the spring when the pin is in so as to present a neat appearance.

Another object is to provide such construction 30 that the supporting frame can be readily and quickly applied to a hat at any point and sufficiently secured thereto.

Referring to the drawings which illustrate my invention Figure 1 shows a hat in section 35 with two of the improved fastening devices applied thereto; Fig. 2 is a view of one of the pins with the supporting frame in section and showing the pin in its inner position; and Fig. 3 is a similar view showing 40 the pin pulled out.

Each device comprises a supporting structure S adapted for engagement with a hat, and a pin P for sliding through the supporting structure to be brought into 45 engagement with the hair. The supporting structure is in the form of a short tube or sleeve 5 having the external threads 6 for receiving outer and inner washer disks 7 and 8. The pin P extends through 50 the sleeve and is encircled by a tension spring 9 within the sleeve and secured at its inner end in an opening 10 through the sleeve and at its outer end is secured in a hole 11 provided through the flattened portion 12 of the pin. The outer end of the

pin is threaded for receiving a suitable head 13. Pin structures are provided at opposite sides of a hat, the hat being perforated at 14 and the pin structures applied therethrough from the outside after removal of 60 the inner washers 8. After such application the inner washers are applied and the hat walls clamped between the washers. The springs 9 normally hold the pins inwardly 65 with their heads in abutment with the outer ends of the sleeves and when the hat is to be worn, the opposite pins are pulled outwardly and the hat then applied to the head and the pins released and guided into the hair, the springs then holding the pins in 70 inner position with the heads against the outer ends of the sleeves. The sleeves should of course be of sufficient length to entirely accommodate the springs when contracted so that no part of the spring will 75 show. At the same time, the sleeves should not extend too great a distance into the hat but should clear the wearer's head. The sleeve therefore extends partly within and partly without the hat and the outer section 80 5' preferably remains unthreaded so as to give a neat appearance and the inner end of this portion forms an abutment for the outer washer against which the hat wall can then be securely clamped by the inner washer. 85 The ends of the pins P may be flattened or otherwise expanded to make the end more or less blunt and to prevent the pins from being entirely withdrawn from their supporting sleeves. I thus provide fastening 90 pins which can be readily and quickly applied to opposite sides of a hat and which coöperate to efficiently hold the hat in place. The part of the pins outside of the hat are very neat in appearance and after the hat 95 has been secured no springs will be visible.

I do not of course desire to be limited to the precise construction and arrangement shown as changes and modifications would be possible which would still come within 100 the scope of the invention as claimed.

I therefore claim the following:

In combination with the wall of a hat, of a tubular sleeve extending through an aperture in said wall and having a threaded exterior, outer and inner washers having threaded engagement with said sleeve and disposed mid-length thereof and clamping the hat wall between them to thus secure the sleeve to the wall, a pin slidable through 105 110

said sleeve and terminating in a head at its outer end, and a spring encircling said pin within said sleeve and connected with said sleeve and pin tending to resist outward movement of said pin, said spring being entirely inclosed by said sleeve when said pin is in its innermost position.

In witness whereof, I hereunto subscribe my name this 3rd day of Sept., A. D., 1912.

FREDERICK W. KRECH.
